UNITED STATES PATENT OFFICE.

MARCUS A. McCRAY, OF MEDIAPOLIS, IOWA.

DESIGN FOR A STAMP OR ENVELOP MOISTENER.

SPECIFICATION forming part of Design No. 35,908, dated May 13, 1902.

Application filed April 17, 1902, Serial No. 103,462. Term of patent 14 years.

To all whom it may concern:

Be it known that I, MARCUS A. McCRAY, a citizen of the United States, residing at Mediapolis, in the county of Des Moines and State of Iowa, have invented and produced a new and original Design for a Stamp or Envelop Moistener, of which the following is a specification.

The invention relates to a new and original design for a stamp and envelop moistener; and it has for its object to provide an ornamental design of that character.

The leading feature of the design consists in the design forming the subject-matter of the accompanying illustration.

The figure of the drawing is a perspective view of a stamp and envelop moistener, showing my new and original design.

Referring to the drawing, 1 designates a stamp and envelop moistener provided with

with an ornamental base 2, having a series of ornamental legs radiating from the center of the base.

The stamp and envelop moistener is provided at its upper portion with an ornamented 25 globular receptacle 3, and it has an arm or pipe extending from the base of the receptacle. The receptacle 3 is provided at its top with a neck 4, and the arm 5 is provided at its outer end with a bowl 6.

What I claim is—

The design for a stamp and envelop moistener as herein shown and described.

In testimony that I claim the foregoing as my own I have hereto affixed my signature 35 in the presence of two witnesses.

MARCUS A. McCRAY.
